WOOL STORAGE AND TRANSPORTING
MECHANISM

Arthur M. Stevens, Methuen, Mass.

Application March 29, 1945, Serial No. 585,539

11 Claims. (Cl. 214—16)

1

This invention relates to apparatus for transferring masses of portable material from one place to another in which overhead and underneath obstructions limit the vertical width of the path through which the transporting means travels.

More particularly the invention relates to apparatus, such as a warehouse, having a plurality of stories in which one of the stories is divided by partitions into compartments and the object of the invention is to provide a traveling crane located in proximity to the floor of the next upper story having hoisting mechanism adapted to travel above any of the compartments of the story therebeneath and capable of transferring portable material from any part of one compartment to another part thereof, or to any other compartment of said lower story or any part of the latter.

The invention is illustrated and described herein with particular reference to warehouses in which wool is sorted and stored in an upper story from which it is dropped through suitable apertures in the floor of the upper story into selected compartments or bins in the story therebeneath.

In usual warehouses for sorting and storing wool the raw wool, which is usually delivered in bales to the warehouse, is placed in an upper story, usually the second story of the warehouse, where impurities are manually removed and the good wool which is sorted as to quality dropped through apertures in the floor of the upper story into compartments or bins, the partitions of which extend from the floor of the lower story to the floor of the upper story. The wool thus dropped into the several bins is manually spread therein throughout the area of the bins. In large warehouses the spreading of the wool in the respective bins requires the work of several hands. One of the purposes of the invention is to provide transporting mechanism under the control of a single operator which will enable him to spread the wool evenly in the respective bins, thus avoiding the necessity of such manual labor.

In usual warehouses hand labor is employed for removing the wool from a bin into a small box truck positioned in an aisle alongside the bin, the loaded truck being then drawn to processing machines in an adjoining building, or loaded from the box truck into a larger truck for transportation to a greater distance.

One of the objects of the invention is to provide transporting mechanisms under the control of a single operator which will enable the wool accumulated in any of the several bins to be transported to another bin or from any bin to

2

a truck located in an aisle extending alongside the several bins.

It will be understood that the invention is not limited to the transportation of wool but may be employed for similarly transferring and transporting other portable materials, whether in the form of loose masses, bales, or other forms of packages.

Another object of the invention is to provide a temporary storage space above the crane for wool or other material dropped through an aperture in the floor of the upper story when the crane is therebeneath so that it will not become tangled with the mechanism of the carriage or bridge.

15 By reason of the present invention the wool sorters are enabled to work uninterrupted and drop the material through the apertures in the floor without regard to the location or operation of the crane in handling the material in the bins 20 of the floor below.

A further object of the invention is to provide transferring or transporting mechanism of the character described in which the traveling crane and hoisting mechanism are electrically operated 25 and under the control of a single operator and in which means are provided for taking up the slack in the electric cable running from the point of control to the several electrically operated mechanisms.

30 These and other objects and features of the invention will more fully appear from the following description and the accompanying drawings and will be particularly pointed out in the claims.

An illustrative embodiment of the invention is 35 shown in the accompanying drawings, in which,

Fig. 1 is a diagrammatic plan view of the lower story of a warehouse having a series of partitions dividing the floor area of the warehouse into a series of bins and leaving an aisle extending longitudinally along one side of the lower story and crane adapted to travel longitudinally of said lower story having a carriage with a suitable hoisting mechanism mounted thereon adapted to travel transversely of the length of the lower story, with a cab for the operator suspended from the crane and provided with means for controlling the operation of the crane, its carriage and the hoisting mechanism mounted thereon, the apertures in the floor of the upper story being indicated by dotted lines;

Fig. 2 is a vertical longitudinal sectional view of the same;

Fig. 3 is a transverse vertical sectional view of the construction shown in Fig. 1;

55 Fig. 4 is an enlarged detail transverse sectional

view of a portion of the construction shown in Fig. 1 illustrating particularly the carriage hoisting mechanism mounted thereon and the storage means which holds temporarily any material which is dropped through an aperture in the floor of the upper story and prevent it from accumulating upon the carriage and the hoisting mechanism thereof, and also showing the take-up for the electric cable;

Fig. 5 is an enlarged detail view, partially in vertical section and partially in elevation, showing particularly the take-up mechanism for the electric cable which controls the mechanism for actuating the grapple of the hoisting mechanism thereof; and,

Fig. 6 is an enlarged diagrammatic plan view of the crane and the electrically actuated carriage and hoisting mechanism thereof and the cable take-up.

The construction illustrated shows diagrammatically in plan a lower story of a warehouse of any suitable length having vertical parallel side walls 1 and 2 mounted upon suitably spaced vertical posts 3. Suitable vertical partitions 4, which divide the floor space into a series of bins, extend from the vertical side wall 2 and terminate at a suitable distance from the opposite side wall 1 to provide an aisle 5 which extends alongside the wall 1. The free ends of said partitions desirably are provided with suitable braces 6 to prevent them from displacement. The upper ends of the partitions 4 terminate a predetermined narrow distance below the floor 7 of the upper story and the supporting beams 8 therefor, which will prevent the cab or grapple from passing over the top thereof from bin to bin. The floor 7 is provided with apertures 9 which preferably are located above the respective bins and through which the sorted wool may be dropped into the respective bins.

Parallel tracks 10, which are mounted upon brackets 11, secured to the vertical posts 3 of the respective side walls 1 and 2, extend longitudinally of the warehouse and support the traveling crane in such manner that its bridge can travel lengthwise of the warehouse in the narrow space above the upper ends of the partitions 4.

The bridge of the traveling crane preferably comprises parallel wide I-beams 12 and 13 the ends of which are connected by suitable girders 14 and 15 having electrically driven rollers 16 which are mounted upon the tracks 10, as in usual constructions. Suitable tracks 17 are mounted upon the inwardly extending lower flanges of the I-beams 12 and 13 of the bridge and extend throughout the length thereof, Figs. 4 and 6. The carriage 18 is provided with suitable rollers 19 which are mounted upon the rails 17 and is adapted to travel transversely of the length of the warehouse at right angles to the direction of travel of the crane.

A cam 20 is suspended from the end portion of the bridge of the crane which is above the aisle and is adapted therefore to travel lengthwise of said aisle in either direction as the crane is moved longitudinally of the warehouse.

The carriage as illustrated in Figs. 4 and 6 comprises parallel side plates 21 and 22 which are rigidly connected together by suitably spaced girders 23 and are provided at their ends with downwardly extending parallel plates 24 and 25 in which the shafts 26 of the rollers 19 are mounted. Suitable electrically driven mechanism for actuating the grapple of the hoisting mecha-

nism is mounted upon the carriage preferably within the space defined by the upper and lower flanges of the I-beams 12 and 13 of the bridge, so that the carriage occupies a minimum of vertical space.

In order to prevent deposition of wool or other material upon the mechanisms of the carriage and bridge, a temporary storage means is provided above the bridge, of such capacity that it can hold the material, which will normally be dropped through any of the openings in the floor for a short period of time long enough for the crane to pass under said opening to pick up or discharge a load. The bottom of this temporary storage means consists of a flat platform 27 mounted above the bridge girders and attached thereto. The platform 27 has downward extensions 28 which overlie the sides of the bridge girder. Beams 8 and/or extensions 29 form the sides of the temporary storage means.

Suitable means are provided for discharging the accumulation of wool or other material from the temporary storage means into the bin directly beneath. When the bridge of the crane passes away from any opening 9, any accumulation in the temporary storage means is scraped off of platform 27 by the beams or a suitable guard 29 which is secured to and depends from the floor 7 in proximity to one of the sides of an opening 9.

Suitable electrically operated mechanism under the control of an operator in the cab 20 is provided for causing the bridge to travel lengthwise of the warehouse and for causing the carriage upon the bridge to travel transversely of the direction of movement of the bridge. Electrically operated hoisting mechanism including a grapple preferably having cooperating sets of forks is mounted upon the carriage and is also under the control of the operator in the cab. The electrically operable mechanism for raising and lowering the grapple is mounted in the carriage within the vertical space defined by the upper and lower flanges of the I-beam girders of the bridge. This is an important feature of the invention as it enables such mechanism to occupy a minimum of vertical space, enabling the carriage to be located in close proximity to the floor beams of the upper story and also to enable the carriage to pass beneath the roof carried by the bridge beneath the apertures in the floor through which the sorted wool is dropped. The forks, which are pivotally mounted upon the grapple frame, are operated through electrically driven mechanisms which are mounted upon the grapple frame to swing them about their pivotal connection in such manner as to engage and release the material which is to be transported in a manner herein-after described.

The construction for raising and lowering the grapple, which is illustrated in detail in Figs. 4 and 6, comprises a pair of suitably spaced winding drums 30 to each of which one end of a cable 31 is attached. The cables pass respectively downwardly beneath and around sheaves 32 upon the grapple frame, and thence upwardly with their upper ends fixedly secured to the respective girders 23 of the carriage. The drums 30 are fixedly secured to a shaft 33 which is journaled in the end plates 23 and is driven from the shaft of a motor 34 through suitable reduction gearing enclosed in a casing 35. The shaft of the motor is provided with a suitable electrically operated brake 36. The drums, the motor and brake are all within the vertical space between the upper and lower planes of the side plates 12 and 13 and

the end plates 23 of the carriage frame so that all the mechanisms of the carriage are within the minimum vertical space between the upper and lower planes of the I-beams of the bridge.

Suitable electrically operated mechanism, which is mounted on the bridge, is provided for propelling the carriage lengthwise of the bridge and consequently transversely of the direction of movement of the bridge. In the preferred construction, illustrated in Fig. 6, a cable 37 is attached at its respective ends to spaced drums 38 and 39 and extends intermediate of the drums over similarly spaced sheaves 40 and 41 mounted upon the side plate 22 of the carriage. The drums 38 and 39 are fixedly secured to a shaft 42 which is driven by a suitable reversible motor 43 mounted upon the bridge. A central drum 44 is rigidly mounted upon the shaft 42 and a cable 45 extends therefrom around a sheave 46 which is mounted upon the end girder 15 of the bridge (Fig. 1), and thence to a spring-backed I-bolt 47 which is secured to the side plate 21 of the carriage (Fig. 6). When therefore the shaft 42 is rotated in one direction the cable 37 will be wound upon the drums 38 and 39 drawing the carriage in one direction and when rotated in the opposite direction will cause the drum 44 to pull the carriage in the reverse direction lengthwise of the bridge.

Usual mechanism well known in the art is provided for conducting currents of electricity to suitable switches in the cab and from said switches to the respective motors comprising (1) the motor for causing the bridge to travel longitudinally of the warehouse; (2) the motor for causing the carriage to travel longitudinally of the bridge; (3) the motor for actuating the hoisting mechanism; and (4) the electric motor for actuating the tines of the grapple fork, and need not be illustrated in detail in the drawings except as to the mechanism for preventing sagging of the section of the cable containing the electric conductors leading to the motor which drives the hoisting mechanism and the conductors of a branch thereof which leads to the motor which actuates the tines of the grapple fork.

In the present construction, as in usual constructions, a cable, which ordinarily is contained in a metallic tube, extends from the switches in the cab to a junction box which is mounted upon the bridge. Conductors extend from this junction box to the motors which respectively drive the hoisting mechanism and the forks of the grapple.

As graphically illustrated in Fig. 5 currents are supplied from a suitable source of power through suitable conductors in a cable 48 to conductor bars 49 carried in a suitable duct which is mounted upon one of the tracks 10 upon which the bridge is mounted and extends longitudinally thereof. Contact members which engage the respective bars are mounted upon the cab and lead therefrom to the switch mechanism in the cab which is suspended from the bridge. A suitable cable, which preferably is enclosed in a pipe (not shown) extends from the switch mechanism 50 in the cab to a junction box 51 which preferably is mounted on the bridge girder 13 approximately midway of its length and a branch of the cable containing the conductors leading to the motors which are carried by the carriage extends from the switch box 51 to the carriage.

Inasmuch as the carriage travels longitudinally of the bridge girders the section of cable running from the junction box 51 to the carriage

must be of sufficient length to reach its attachment to the carriage when the carriage is at the most remote position of its travel in each direction from the junction box 51. When the carriage is moved from such remote positions toward the junction box 51 the section of the cable in usual constructions sags down in the form of a progressively lengthening loop. If such sagging were permitted in the present apparatus, in which the bridge and the carriage travel over obstructions such as the vertical partitions forming the walls of the bins, the sagging loop of the cable would engage such obstructions and not only be injured thereby but also might interfere with the proper operation of the crane mechanism.

In the present construction as illustrated in detail in Figs. 4, 5, and 6, the outer lower flange of the I-beam 13 is provided with or has attached to it an extension extending lengthwise thereof having an upturned flange 52 and the outer upper flange of the I-beam has similarly extended or has secured to it a plate 53 having a down-turned flange 54 complementary to the flange 52 providing lower and upper tracks for a cable-supporting trolley.

The trolley as illustrated in side elevation and plan in Figs. 5 and 6 comprises a plate 55 which has secured to it adjacent each end inwardly projecting stud shafts upon which grooved lower rollers 56 and grooved upper rollers 57 are mounted to engage and travel along the respective flanges 52 and 54. The plate 55 is provided midway of its length with a stud shaft 58 which forms a journal for a grooved pulley 59. The section 60 of the electric cable is led from the junction box 51 along and is supported upon the lower outer flange of the I-beam 13 of the bridge and passes in the form of a loop around the pulley 59 and extends to and is attached to the inwardly inclined upper end of a U-shaped vertical bar 61 which underlies the lower flange of the I-beam 13 and is secured to the frame of the carriage. The electric cable extends from such attachment along the U-shaped bar 61 and thence is provided with a branch conductor 62 leading to a switch box 63 from which it is connected by a conductor 64 to the motor for driving the hoisting drum. Another branch 65 leads to the brake 36 and a third branch conductor leads through a suitable switch box 66 and conductor 66a through a rotatable connection 67 to an electric cable 68 which is wound upon a spring drum 69 and leads to the motor 70 which actuates the tines of the grapple fork.

Suitable means are provided for causing the trolley to travel lengthwise of the bridge as the carriage is moved back and forth upon it to maintain such tension upon the electric cable 60 as to prevent the sagging thereof during the movements of the carriage. In the construction illustrated in Fig. 6 the trolley plate 55 is connected preferably through a spiral spring 71 to a flexible steel cable 72 which is adapted to be wound upon a drum 73 which is fixedly secured to the shaft 42, or the cable may be wound upon a spring actuated take-up drum of well known construction. The cable 72 is so wound upon the take-up drum 73 that as the carriage travels away from the drum the trolley will be moved by the tension upon the electric cable 60 away from the drum at half the speed of the carriage. When the carriage is moved toward the drum the steel cable 72 will be wound upon the drum 73 and draw the trolley toward the drum thereby maintaining

sufficient tension upon the section 60 of the cable to prevent it from sagging below the bridge of the crane and thus will prevent the cable from engaging the partitions or other obstructions beneath the carriage.

Any suitable grapple construction may be employed. In the preferred construction graphically illustrated herein the motor 70 is of a reversible type and actuates a gear pump 74 which alternately supplies oil under pressure through suitable pipes 75 and 76 to opposite ends of cooperating cylinders 77 and 78 which are mounted upon the frame of the grapple and which actuate respectively pistons having piston rods connected respectively to like cross heads 79 which in turn through suitable mechanism rotate shafts 80 and 81 having complementary arcuate tines 82 and 83 toward and from each other to grasp and release the material. Desirably means are provided for insuring the proper conjoint operation of the shafts 80 and 81 such as sprockets 84 and 85 around which extend a crossed chain 86 having a slotted link connection 87 through which one of the leads of the chain passes.

In the operation of the system wool is sorted in the upper story of the warehouse and is selectively dropped through suitable apertures 9 in the floor into the respective bins. As the material accumulates in the bin the bridge of the crane is automatically moved under the control of the operator over a bin in which it is desired to distribute the pile of wool or other material evenly throughout the area of the bin; the carriage is then moved over the pile, the grapple caused to descend under the control of the operator, and the grapple thereupon actuated by the operator to cause the tines to approach each other and gather the mass of the material therebetween. The loaded grapple is then hoisted and the operator by controlling the movement of the bridge and carriage can transfer it to any portion of the bin thereby maintaining a substantial level of material in the bin and insuring complete filling of the bin to any desired height. The grapple either empty or loaded can be moved from bin to bin only when first carried over the aisle, the partitions between the bins being purposely built so high that there is just room for the bridge of the crane only to pass over the partition. If therefore it is desired to transfer the material from one bin to another the operator can manipulate the bridge of the crane, the carriage, and the grapple in the same manner to engage a mass of material in one bin and lift the grapple to a sufficient height to free it from the pile, then cause the carriage to carry the grapple over the aisle and by moving the bridge and carriage deposit it in another bin, or the material may be similarly transferred from any bin to a truck standing in any portion of the aisle.

If during the respective movements of the bridge and carriage above described the bridge is positioned beneath an aperture any wool being dropped through the aperture will be held in the temporary storage space above the platform 21 while the bridge is beneath an aperture. Upon movement of the bridge in either direction such wool as has accumulated upon the platform 21 will be scraped off in the manner aforesaid.

By reason of the take-up mechanism for the electric cable during the traveling movements of the carriage sagging of the cable is prevented from engaging the partitions or other obstructions as the carriage is moved over the partitions between the bins.

It will be obvious from the foregoing description that the present invention comprises means for transferring wool or other material which can be economically operated, which will avoid the necessity of manually distributing wool or other materials in the respective bins and which will enable the material to be transferred from one bin to another or to be loaded conveniently upon a truck placed in the aisle.

It will be understood that while the invention is particularly described herein as for the storage and transfer of wool, the mechanism may be employed in any construction in which it is desirable to have the mechanism carried by a crane 10 to occupy a minimum amount of space between overhead and underneath obstructions and in which it is desirable or necessary to avoid a sagging cable which during the movement of the bridge and carriage of the crane will be likely to engage an obstruction or to injure a person employed beneath the path of the carriage of the crane.

It will therefore be understood that the particular embodiment of the invention shown and 15 described herein is of an illustrative character and is not restrictive of the meaning and scope of the following claims.

Having thus described the invention, what is 20 claimed as new and desired to be secured by Letters Patent is:

1. Apparatus of the class described comprising a warehouse having a lower story for the storage of portable material and a superposed upper story for sorting the material having a floor provided with openings through which the sorted material may be dropped, vertical partitions in said lower story extending from a side wall thereof and terminating at such distance from the opposite wall as to provide an aisle along the latter and of such height as to leave such narrow space between the upper ends of said partitions and the floor of the upper story as will prevent the passage of the grapple or cab of a crane therethrough, a traveling crane having a bridge mounted upon suitable tracks to travel longitudinally of the space between the upper ends of said partitions and the floor of the upper story and having a cab for the operator depending into said aisle, a traveling carriage mounted on said bridge movable transversely of the direction of movement of the bridge provided with a vertically movable grapple fork, and means under control of the operator for actuating the mechanisms of said crane and fork to transfer masses of said material to different portions of the respective bins and from a bin to a truck located in the aisle.

2. Apparatus of the class described comprising a warehouse having a lower story for the storage of wool or like material, a superposed upper story for sorting the material having a floor provided with one or more openings through which the sorted material may be dropped respectively into bins formed by vertical partitions in said lower story of such height as to leave such narrow space between the upper ends of the partitions and the floor of the upper story as will prevent the passage of the grapple or cab of a crane therethrough, a traveling crane having a bridge mounted on suitable tracks to travel longitudinally of the warehouse between the upper ends of said partitions and the floor of the upper story, a traveling carriage mounted on said bridge movable transversely of the direction of movement of said bridge provided with a vertically movable grapple fork, means mounted on or above said

bridge for temporarily holding material being dropped through a floor opening so that it will not become tangled in the mechanism of the carriage when the carriage is beneath said opening.

3. Apparatus of the class described comprising a warehouse having a lower story for the storage of wool or like material, a superposed upper story for sorting the material having a floor provided with one or more openings through which the sorted material may be dropped, vertical partitions in said lower story extending from a side wall thereof and terminating at such distance from the opposite wall as to provide an aisle along the latter and of such height as to leave such narrow space between the upper ends of said partitions and the floor of the upper story as will prevent the passage of the grapple or cab of a crane therethrough, a traveling crane having a bridge mounted upon suitable tracks to travel longitudinally of the warehouse within the space between the upper ends of said partitions and the floor of the upper story and having a cab for the operator depending into said aisle, a traveling carriage mounted on said bridge movable transversely of the direction of movement of said bridge provided with a vertically movable grapple fork, and having a platform mounted on said bridge so positioned as to temporarily hold material dropped through a floor opening and prevent it from being deposited upon the mechanisms of said carriage when the carriage is beneath such opening, and means under the control of the operator for actuating the mechanisms of said crane and fork to transport masses of said material to different portions of the respective bins or from a bin to a truck located in the aisle or from one bin through said aisle to another bin.

4. Apparatus of the class described comprising a warehouse having a lower story for the storage of wool or like material, a superposed upper story for sorting the material having a floor provided with one or more openings through which the sorted material may be dropped, vertical partitions in said lower story extending from a side wall thereof and terminating at such distance from the opposite wall as to provide an aisle along the latter and a series of bins and of such height as to leave a narrow space between the upper ends of said partitions and the floor of the upper story, a traveling crane having a bridge mounted upon suitable tracks to travel longitudinally of the warehouse within the space between the upper ends of said partitions and the floor of the upper story and having a cab for the operator depending into said aisle, a traveling carriage mounted on said bridge movable transversely of the direction of movement of said bridge provided with a vertically movable grapple fork and having a platform mounted on said bridge so positioned as to temporarily hold material dropped through a floor opening and prevent it from being deposited upon the mechanisms of said carriage when the carriage is beneath said opening, means for removing the material dropped upon said platform upon movement of the bridge from beneath said opening, and means under the control of the operator for actuating the mechanisms of said crane and fork to transport masses of said material to different portions of the respective bins and from a bin to a truck located in the aisle.

5. Apparatus of the class described comprising a warehouse having a lower story for the storage of wool or like material, a superposed upper story

for sorting the material having a floor provided with one or more openings through which the sorted material may be dropped, vertical partitions in said lower story extending from a side wall thereof and terminating at such distance from the opposite wall as to provide an aisle along the latter and a series of bins and of such height as to leave a narrow space between the upper ends of said partitions and the floor of the upper story, a traveling crane having a bridge mounted upon suitable tracks to travel longitudinally of the warehouse within the space between the upper ends of said partitions and the floor of the upper story and having a cab for the operator depending into said aisle, a traveling carriage mounted on said bridge movable transversely of the direction of movement of said bridge provided with a vertically movable grapple fork and having a platform mounted on said bridge so positioned as to temporarily hold material dropped through a floor opening and prevent it from being deposited upon the mechanisms of said carriage when the carriage is beneath said opening, guards mounted upon and extending downwardly from the floor of the upper story and terminating in proximity to said platform for removing the material deposited upon said platform upon movement of the bridge from beneath an opening, and means under the control of the operator for actuating the mechanisms of said crane and fork to transport masses of said material to different portions of the respective bins and from a bin to a truck located in the aisle.

6. Apparatus of the class described comprising a warehouse having a lower story and a superposed upper story, vertical partitions in said lower story of such height as to leave a narrow space between the upper ends of said partitions and the floor of the upper story, parallel ways extending respectively along and in proximity to the sides of said lower story above the upper ends of said partitions, a crane comprising a bridge mounted on said ways and movable lengthwise thereof having deep parallel girders provided with lower flanges extending toward each other, a carriage mounted on the lower flanges of said bridge to travel transversely of the direction of movement of said bridge, vertically movable grapple mechanism mounted on said carriage, and means for supporting and actuating said carriage and grapple mounted respectively on said bridge and carriage and lying within the vertical space between the upper and lower horizontal planes of said bridge girders.

7. Apparatus of the class described comprising a warehouse having a lower story and a superposed upper story, vertical partitions in said lower story of such height as to leave a narrow space between the upper ends of said partitions and the floor of the upper story, parallel ways extending respectively along and in proximity to the sides of said lower story above the upper ends of said partitions, a crane comprising a bridge mounted on said ways and movable lengthwise thereof having deep I-beam girders, a carriage mounted upon the inner lower flanges of said I-beam girders to travel transversely of the direction of movement of said bridge, vertically movable grapple mechanism mounted on said carriage, electrically operable mechanism respectively for actuating said carriage and for raising and lowering said grapple mounted on said bridge and carriage and lying within the vertical space between the upper and lower horizontal planes of said bridge girders.

8. Apparatus of the class described comprising a warehouse having a lower story and a superposed upper story, vertical partitions in said lower story of such height as to leave a narrow space between the upper ends of said partitions and the floor of the upper story, parallel ways extending respectively along and in proximity to the sides of said lower story above the upper ends of said partitions, a crane comprising a bridge mounted on said ways and movable lengthwise thereof having deep I-beam girders, a carriage mounted upon the inner lower flanges of said I-beam girders to travel transversely of the direction of movement of said bridge, vertically movable grapple mechanism mounted on said carriage, electrically operable mechanism respectively for actuating said carriage and for raising and lowering said grapple mounted on said carriage and lying within the vertical space between the upper and lower horizontal planes of said bridge girders, and a roof mounted on the upper flanges of said bridge girders so positioned as to prevent material dropped through an opening in the floor from being deposited upon the carriage when it is beneath said opening.

9. Transporting mechanism for a warehouse having suitably spaced partitions dividing the same into a plurality of compartments and of such height as to leave a narrow space between the upper ends of said partitions and a superstructure of said warehouse, parallel ways in said space extending respectively along and in proximity to the sides of the warehouse, a crane having a bridge mounted to travel lengthwise of said warehouse over said partitions, means for actuating said bridge, a carriage mounted on said bridge to travel at right angles to the direction of travel of the bridge, hoisting mechanism including an electric motor mounted on said carriage, a power cable having a conductor for supplying an electric current to said motor, anchored to said bridge and having a flexible section at least as long as the distance of travel of the carriage from said anchorage secured to said carriage, means for preventing undue sagging of said flexible cable section during the traveling movements of said carriage, comprising a trolley mounted to travel on said carriage in the directions of movement thereof having a pulley embraced by a loop in said flexible cable section, and means for actuating said trolley coordinated with the traveling movements of said carriage to maintain sufficient tension upon said flexible cable section as to prevent sagging thereof below the bridge of the traveling crane.

10. Transporting mechanism for a warehouse having suitably spaced partitions dividing the same into a plurality of compartments and of such height as to leave a narrow space between the upper ends of said partitions and a superstructure of said warehouse, parallel ways in said space extending respectively along and in proximity to the sides of the warehouse, a crane comprising a bridge mounted to travel lengthwise of said warehouse over said partitions, having deep I-beam girders, a carriage mounted upon the in-

ner lower flanges of said I-beam girders, hoisting mechanism mounted on said carriage including an electric motor, winding drums actuated thereby having cables supporting a grapple fork mechanism provided with an electric motor and means operable thereby for actuating the tines of said grapple fork, a power cable, having conductors for supplying electric currents to the respective motors, anchored to said bridge midway of the length of said bridge, and having a flexible section at least as long as the distance of travel of the carriage in either direction away from said anchorage secured to said carriage with branch conductors leading to the respective motors, means for preventing the sagging of said flexible cable section during the traveling movements of the carriage comprising a trolley mounted upon the outer flange of one of said bridge girders to travel lengthwise thereof provided with a pulley embraced by a loop in said flexible cable section positioned to cause the lower leg of the loop to overlie the outer flange of the I-beam girder, and means for actuating the trolley coordinated with the traveling movements of the carriage to maintain sufficient tension upon said flexible cable section to prevent sagging of the upper leg thereof below the lower flange of said I-beam girder.

11. Transporting mechanism for a warehouse having suitably spaced partitions dividing the same into a plurality of compartments and of such height as to leave a narrow space between the upper ends of said partitions and a superstructure of said warehouse, parallel walls in said space extending respectively along and in proximity to the sides of the warehouse, a crane comprising a bridge having parallel deep I-beam girders mounted to travel lengthwise of said warehouse over said partitions, means for actuating said bridge, a carriage mounted on said bridge to travel at right angles to the direction of travel of the bridge, vertically movable hoisting mechanism mounted on said carriage, electric motors and means operable thereby for actuating the carriage and hoisting mechanism respectively, a flexible power cable having conductors leading from a source of electricity to the respective motors on the carriage having a section thereof at least as long as the distance of travel of the carriage secured at one end to the bridge and connected adjacent its other end to said carriage with branches of the conductors of said cable leading to the respective motors, means for taking up slack in said cable section comprising a trolley mounted to travel on said bridge lengthwise thereof having a pulley positioned above the lower outer flange of said I-beam embraced by a loop in said cable section and so positioned that the lower lead of said loop will be supported by the lower flange of the I-beam, and means for actuating said trolley coordinated with the movements of said carriage to maintain sufficient tension upon the cable as to prevent sagging thereof below the lower flange of said I-beam.
